US0D1091116S

(12) United States Design Patent (10) Patent No.: US D1,091,116 S
(45) Date of Patent: * Sep. 2, 2025

(54) BAG

(71) Applicant: HOBONICHI CO., LTD., Tokyo (JP)

(72) Inventor: Shigesato Itoi, Tokyo (JP)

(73) Assignee: HOBONICHI CO., LTD., Tokyo (JP)

() Term: 15 Years

(21) Appl. No.: 29/861,488

(22) Filed: Nov. 30, 2022

(30) Foreign Application Priority Data

Jun. 8, 2022 (JP) ..... 2022-012266 D

(51) LOC (15) Cl. 03-01

(52) U.S. Cl.

USPC D3/243; D3/284

(58) Field of Classification Search

USPC D3/226, 231, 232, 233, 239, 240,

(57) CLAIM

The ornamental design for a bag as shown and described.

DESCRIPTION

FIG. 1 is a front view;

FIG. 2 is a rear view;

FIG. 3 is a right side view;

FIG. 4 is a top view;

FIG. 5 is a bottom view;

FIG. 6 is a perspective view which is seen from front;

FIG. 7 is a perspective view which is seen from rear;

FIG. 8 is a perspective view with the lid opened which is seen from front;

FIG. 9 is a perspective view with the lid opened which is seen from rear;

FIG. 10 is a front view with the lid opened;

FIG. 11 is a rear view with the lid opened;

FIG. 12 is a right side view with the lid opened;

FIG. 13 is a top view with the lid opened; and,

FIG. 14 is a bottom view with the lid opened.

1 Claim, 8 Drawing Sheets
